STATIC ELIMINATOR

Games Slayter, Newark, Ohio

Application February 2, 1942, Serial No. 429,216

8 Claims. (Cl. 175—264)

This invention relates generally to electric discharge apparatus and refers more particularly to improvements in equipment of the type employed to eliminate the interference caused by static electricity.

It has been proposed to eliminate interference resulting from static conditions by providing an electric discharge of alternating polarity between an emitting electrode and a collecting electrode so arranged in an alternating current circuit with respect to the electrically charged object that ions drift from the electrostatic field between the electrodes to neutralize the charge on the object.

Although electric discharge equipment operating on the principle briefly outlined above has proved successful under widely varying conditions, nevertheless, the rate at which one electric discharge device is capable of operating to effect neutralization is not always sufficient to neutralize a relatively fast moving heavily charged material. This limitation is overcome to some extent by providing a series of electric discharge devices but this procedure complicates the installation and increases the cost of the equipment as well as the expense of operation.

It is, therefore, one of the principal objects of this invention to overcome the above limitation without appreciably increasing the cost of the equipment or the expense of operating the latter by providing an electric discharge device having means for neutralizing a large quantity of charge of either polarity on a fast moving object before the object registers with the electrostatic field produced by the emitting and collecting electrodes.

More particularly the present invention contemplates supporting one or more grounded pointed rods or electrodes in such relationship to the charged body that when the potential difference between the body and ground exceeds the "onset" potential of the pointed electrodes, an electric discharge is created from the pointed ends of the electrodes and this discharge reduces the potential of the object to the "onset" potential of the pointed electrodes. The "onset" potential of the pointed rods is usually small as compared to the total charge on the object and the electrical charge on the object represented by this "onset" potential is readily neutralized by the electric discharge device when the object has advanced to a position in registration therewith.

The foregoing, as well as other objects, will be made more apparent as this description proceeds,

especially when considered in connection with the accompanying drawing wherein:

Figure 1 is a side elevational view partly in section of electric discharge equipment constructed in accordance with this invention;

Figure 2 is a cross sectional view taken on the line 2—2 of Figure 1 and showing the equipment in operative relation to a charged object; and

Figure 3 is a diagrammatic perspective view 10 of the electric discharge equipment and showing a part of the electrical circuit employed.

Although the electric discharge equipment forming the subject matter of this invention may be advantageously used in practically any case where it is desired to release or neutralize electrostatic charges, nevertheless, it finds particular utility when used for the purpose of removing or neutralizing static charges on moving objects and especially rapidly moving objects. For the purpose of illustrating this invention, therefore, I have diagrammatically shown in Figure 2 a travelling object 10 which may be a sheet of paper or any other material adapted to acquire an electric charge of either polarity.

25 It is desired to neutralize static charges on travelling sheets of material because these charges often times seriously interfere with processing the material and this invention insures expedient neutralization of charges of either polarity on the sheet of material 10 as the latter is advanced along its path of travel. In general, the equipment for accomplishing the above results comprises an electric discharge device 11 having a plurality of pointed emitting electrodes 12 arranged in spaced relation to each other in a single row and having collecting electrodes 13, respectively, supported at opposite sides of the emitting electrodes in lateral spaced relation to the latter.

40 As shown in Figure 3, the electrodes are connected in an electric circuit 14 which includes an alternating current transformer 15 having a primary winding 16 connected to a source of alternating current and having a secondary winding 16'. One end of the secondary winding 16' is grounded as at 17 and the other end of the secondary winding is electrically connected to each of the emitting electrodes 12. The collecting electrodes 13 are arranged in the circuit 14 in such a manner that they are also connected to the ground 17. As a result of the above circuit arrangement, a difference of alternating potential is connected to the emitting electrodes 12 and the collecting electrodes 13.

45 The difference of potential is predetermined

in dependence upon the spacing between the emitting electrodes 12 and the collecting electrodes 13 so that an electric discharge of alternating polarity takes place between the pointed ends of the emitting electrodes 12 and the collecting electrodes. In other words, the arrangement is such that electrostatic fields of opposite polarity are produced between the electrodes on successive half cycles of operation so that both positive and negative charges are available in the gap between the electrodes. If desired, a suitable condenser 18 may be connected in the circuit 14 to equalize the quantities of both positive and negative charges produced in the gap between the electrodes on successive half cycles of operation.

The electric discharge device 11 is shown in Figure 2 as positioned in relatively close proximity to the underside of the sheet of material 10 so as to influence any electric charge on this sheet of material. The relationship between the electrostatic field produced by the device 11 and the sheet of material 10 is such that when the latter is charged with a negative polarity, positive charges drift from the electrostatic field to the sheet of material 10 during the positive half cycle of operation of the device 11. Thus, during each positive half cycle of operation of the electric discharge device 11, positive charges are supplied to the negatively charged sheet of material 10 and the latter eventually becomes neutralized. On the other hand, if the sheet of material 10 carries a positive charge, negative charges are released from the electrostatic field during the negative half cycle of operation of the device 11 and are supplied to the sheet of material 10 to neutralize the latter. It follows, therefore, that the electric discharge device 11 acts to neutralize the sheet of material 10 regardless of the polarity of the charge on the latter.

In some instances the quantity of electrical charge on the sheet of material 10 and the rate of travel of this sheet is such that the electric discharge device 11 does not operate with sufficient rapidity to completely neutralize the electric charge on the sheet of material 10. In order to overcome this objection, the action of the electric discharge device 11 is supplemented by one or more rows of pointed discharge electrodes 19. Although the number of rows of discharge electrodes 19 are not critical and may be varied to suit different conditions, nevertheless, I have shown two distinct rows of discharge electrodes 19 herein for the purpose of illustration.

In general, the two rows of discharge electrodes 19 are spaced laterally from each other a sufficient distance so that the electrodes in one row do not interfere with the electrodes in the other row and the electrodes in each row are spaced from each other a sufficient distance so that they do not interfere with one another. In addition, the electrodes in each row are electrically connected in series and are also electrically connected to the ground 17. In the present instance the discharge electrodes 19 are carried by the right hand collecting electrode 13 shown in Figure 2 and are pointed toward the underside of the sheet of material 10. It may be pointed out at this time that both rows of the discharge electrodes 19 are spaced in advance of the adjacent collecting electrode 13 a sufficient distance that they do not interfere with the electrostatic field produced between the emitting electrodes 12 and the collecting electrodes 13.

Owing to the above construction, the discharge electrodes 19 operate to neutralize a substantial

quantity of the electric charge on the sheet of material 10 before the latter comes under the influence of the electrostatic field produced by the electric discharge device 11. It will, of course, be understood, however, that the pointed discharge electrodes 19 will not entirely neutralize the charge on the sheet of material 10 because these electrodes have a certain resistance which is commonly referred to as the "onset" potential characteristic. This potential characteristic varies in dependence on the sharpness of the emitting tips of the discharge electrodes and, in the present instance, the emitting tips are very sharp. As a result, the electrodes 19 are very sensitive and function to initiate the desired electric discharge upon a relatively small potential difference between the sheet and discharge electrodes. This action is desirable because it renders it possible to more nearly neutralize the charge on the sheet before the latter registers with or comes under the influence of the ionic field produced by the electric discharge device 11.

It follows from the above that if the electric charge on the sheet of material 10 is sufficient to cause the sheet to have a potential with respect to ground greater than the "onset" potential for electrical discharge from the pointed electrodes 19, then an electric discharge takes place at the pointed ends and the potential of the paper with respect to ground is thereby reduced to the "onset" potential of the pointed discharge electrodes 19. The electric charge remaining on the sheet of material 10 is neutralized by the electrostatic field produced by the electric discharge device 11 and, as a result, the charge on the sheet of material 10 is completely neutralized.

Assuming, for example, that the electric charge on the sheet of material 10 is of negative polarity, it will be noted that the discharge electrodes 19 are of a positive polarity with respect to the sheet 10 because they are connected to ground. As a result, an electric discharge is produced between the pointed ends of the discharge electrodes 19 and the sheet 10 and electrons are drawn from the sheet 10 tending to reduce the potential of the sheet to the "onset" potential of the pointed discharge electrodes 19. It may be pointed out that the electrons approaching the points of the electrodes 19 are accelerated by the more intense field in the regions of the points and this produces ionization. The positive ions thus produced are forced back toward the sheet of material 10 because the latter is of negative polarity and, accordingly, these positive ions assist in effecting neutralization of the charge on the sheet of material 10.

Assuming now that the charge on the sheet 10 is of a positive polarity, it will be noted that the electrodes 19 will be of a negative polarity with respect to the sheet 10. This results in an electric discharge from the pointed ends of the electrodes 19 to the sheet 10 and causes electrons to accumulate on the sheet 10 tending to neutralize the latter. Thus, it will be apparent that the combination of the electrodes 19 and the electric discharge device 11 renders it possible to completely neutralize the charge on the sheet 10 even though this charge is relatively heavy and even though the rate of travel of the sheet is relatively fast.

The specific construction of the electric discharge device 11 selected herein for the purpose of illustration is similar to the electric discharge

device shown and described in the John Thomay application, Serial No. 413,965, filed October 7, 1941. Briefly, the emitting electrodes 12 are anchored at their radially inner ends in a tube 20 of dielectric material and are connected to an electrical conductor 21 supported in the tube 20 diametrically opposite the radially inner ends of the emitters 12. The electrical connection between the emitters 12 and the electrical conductor 21 comprises a sleeve 22 of semi-conducting material and this material is supported on a cylinder 23 of dielectrical material. The sleeve 22 may be either a semi-conducting ink or a semi-conducting paper and in either case possesses sufficient resistive characteristics to not only assist in controlling the electric discharge but also functions as a resistance between adjacent emitting electrodes 12. As a result, the current drawn by any one emitting electrode is limited and this is advantageous because it minimizes the tendency for the emitters to become overloaded to the point of arcing.

The electrical conductor 21 projects through one end of the dielectric tube 20 and is electrically connected to the secondary coil 16' of the alternating current transformer 15 in the manner shown in the diagram in Figure 3. After the electrical conductor 21 and the cylinder 23, with the semi-conducting material 22 thereon, are assembled in the tube 20, the opposite ends of the latter are sealed with suitable plugs 24. These plugs are formed of a dielectric material and extend beyond the opposite ends of the tube 20 a sufficient distance to enable the device to be readily mounted. The collecting electrodes 13 are supported at opposite ends in end plates 25 which are also formed of dielectric material. The end plates 25 are apertured to respectively receive the projecting plugs 24 and are preferably rigidly secured to the tube 20. This construction is advantageous because it provides for sealing the electrical conductor and its electrical connection to the emitting electrodes from the atmosphere so that the discharge device will operate satisfactorily in moisture laden atmospheres without the danger of short circuiting.

It is also important to control the electric discharge in the gap between the emitting electrodes 12 and the collecting electrodes 13 in order to prevent this discharge from becoming disruptive in nature. In other words, it is desired to provide a diffuse discharge in the gap and this discharge is one which is free from sparking, arcing and streamering.

The diffuse discharge is obtained by controlling the maximum current tendency which can occur in the gap between the emitting electrodes and the collecting electrodes. This control is dependent on a number of variables which vary in dependence upon different uses of the electric discharge device and to some extent on the power supplied to the circuit 14. Therefore, it is not practical to define specific values for these variables which will afford the maximum efficiency of operation under all conditions. However, an electric discharge device constructed in accordance with the following specifications has been found to produce the desired diffuse discharge in the gap between the electrodes. It is to be understood, however, that the specific values noted below are merely for the purpose of illustrating one particular use of the electric discharge device and should not be considered as limiting this invention.

Assuming for the purpose of this description

a 10,000 volt transformer is used in the circuit and that this transformer has an operating output of approximately 200 microamperes when the primary is connected to a 110 volt alternating current source, it has been found that the tips of the emitting electrodes 12 should be approximately three-fourths of an inch from the collecting electrodes 13. It has also been found that the tip diameter of the emitting electrodes should be relatively small and particular satisfactory results have been obtained by forming the tips of the emitting electrodes 12 of approximately two thousandths of an inch in diameter. Also adjacent emitting electrodes 12 should be spaced from each other a sufficient distance that the discharge from the tip of one emitting electrode does not interfere with the discharge from the tip of adjacent electrodes.

The blocking condenser 18 employed in the circuit 14 to equalize the discharges of opposite polarities may be of a relatively small capacity, and I have found that a 2,000 volt condenser having approximately .01 microfarad capacity is satisfactory under average conditions of operation.

The resistivity of the electrical connection 23 between the emitting electrodes 12 and the electrical conductor 21 is not particularly critical. However, it is desired to embody some resistance in the circuit because it has been found that such practice stabilizes the operation of the device and assists in obtaining a diffuse discharge over a long period of use with the minimum attention. For the purpose of illustration a resistance of approximately 200 megohms is satisfactory to perform the desired results.

The pointed discharge electrodes 19 are carried by one of the collecting electrodes 13 and are electrically connected to the latter collecting electrode in order to have the same potential as this electrode. As shown in Figure 3, the discharge electrodes in each row are anchored to a conducting rod 26 in such a manner that the discharge electrodes in each row are electrically connected together in series. The two conductor rods 26 are connected together at longitudinally spaced points by means of a conductor rod 27 and the rod 26 adjacent the collecting electrode 13 is similarly connected to the electrode 13 by means of conductor rods 28. Thus, it will be seen that the discharge electrodes 19 form a unit with the electric discharge device 11.

The spacing between adjacent rows of discharge electrodes 19 and the spacing between the electrodes in each row is such that the electrostatic field at the tip of any one of the electrodes is not disrupted or affected by the discharge from the tip of adjacent electrodes. This spacing will depend to some extent on the distance between the tips of discharge electrodes 19 and the travelling sheet of material 10. However, in most applications the distance between adjacent electrodes 19 should be within the range of one-quarter inch to one-half inch. Also the distance between the electric discharge electrodes 19 and the device 11 is predetermined so that the discharge electrodes 19 have no effect on the electrostatic field in the gap between the emitting electrodes 12 and the collecting electrodes 13. In addition, the number of discharge electrodes 19 is determined for each application so that the current is equally divided between a sufficient number of electrodes to avoid overloading any one electrode to the point where the discharge becomes disruptive and produces streamering.

arching and sparking conditions. This is important because it enables the equipment to be safely used under practically any existing conditions.

What I claim as my invention is:

1. Electric discharge equipment comprising an emitting electrode and a collecting electrode connected in a circuit with a source of alternating potential in a manner to provide an electric discharge of alternating polarity from the emitting electrode to the collecting electrode, and a discharge electrode connected in the circuit and having the same potential as the collecting electrode.

2. Electric discharge equipment comprising a row of pointed emitting electrodes spaced from each other and serially electrically connected together, a collecting electrode supported on each side of the row of emitting electrodes in such relation to the pointed ends of the emitting electrodes to enable a discharge of electricity from the pointed ends of said emitting electrodes to the collecting electrodes, and a second row of pointed discharge electrodes spaced laterally from the row of emitting electrodes and electrically connected to said collecting electrodes.

3. Electric discharge equipment comprising an emitting electrode and a collecting electrode connected in a circuit with a source of alternating potential and spaced from each other to provide an electric discharge of alternating polarity in the gap between the electrodes, means in the circuit providing an electric discharge in the gap of only one polarity at one time, and an additional discharge electrode having the same potential as the collecting electrode and spaced sufficiently from the emitting electrode to be substantially free from the electrostatic field in the gap between the emitting and collecting electrodes.

4. Electric discharge equipment comprising a row of pointed emitting electrodes spaced from each other and serially electrically connected together, an electric circuit including the emitting electrodes and a source of alternating potential, a common collecting electrode for said emitting electrodes and connected in the circuit in such spaced relation to the pointed ends of the emitting electrodes to provide an electric discharge of alternating polarity in the gap between said electrodes, and a row of discharge electrodes extending in the same general direction as the emitting electrodes and having the same polarity as the collecting electrode, said discharge electrodes being spaced laterally from the emitting electrodes a sufficient distance to be substantially free from the influence of the electrostatic field in the gap between the emitting and collecting electrodes.

5. Electric discharge equipment for neutralizing a charge of electricity on a travelling object, comprising a discharge electrode having a pointed end directed toward the object and so positioned with respect to the object that an ionic field is produced between the point and charged object which reduces the potential of the object to the "onset" potential of the pointed electrode, and

means spaced from the pointed electrode in the direction of travel of the object for producing an electric discharge of alternating polarity in such relationship to the object to neutralize the charge remaining on the object regardless of the polarity of this charge.

6. Electric discharge equipment for neutralizing a charge of electricity on a travelling object, comprising a row of pointed discharge electrodes spaced from each other and positioned to one side of the path of travel of the object with the pointed ends directed toward the object, the spacing between the pointed ends and object being predetermined to produce an electric discharge between the pointed ends of the electrodes and object and thereby reduce the charge on the object to the "onset" potential of the pointed electrodes, and means spaced from the row of discharge electrodes in the direction of the travel of the object for producing an electric field of alternating polarity in proximity to the object to thereby neutralize the charge remaining on the object.

7. Electric discharge equipment for neutralizing a charge of electricity on a travelling object, comprising a discharge electrode having a pointed end directed toward the object and so positioned with respect to the object that an ionic field is produced between the point and charged object which reduces the potential of the object to the "onset" potential of the pointed electrode, a collecting electrode spaced from the discharge electrode in the direction of travel of the object and having the same potential as the discharge electrode, an emitting electrode spaced from the collecting electrode and connected to a source of alternating potential sufficient to produce an electric discharge of alternating polarity between the emitting electrode and collecting electrode, said emitting and collecting electrodes being so positioned with respect to the object that the electrostatic field in the gap between the emitting and collecting electrodes neutralizes the charge remaining on the object.

8. Electric discharge equipment for neutralizing a charge of electricity on a travelling object, comprising a row of pointed discharge electrodes spaced from each other and positioned to one side of the path of travel of the object with the pointed ends directed toward the object, the spacing between the pointed ends and object being predetermined to produce an electric discharge between the pointed ends of the electrodes and object and thereby reduce the charge on the object to the "onset" potential of the pointed electrodes, a row of emitting electrodes spaced from the row of discharge electrodes in the direction of travel of the object and connected to a source of alternating potential, a collecting electrode electrically connected to the row of discharge electrodes and operatively positioned with respect to the emitting electrodes and object to produce an electric discharge of alternating polarity between the emitting electrodes and collecting electrode sufficient to neutralize the charge remaining on the object.

GAMES SLAYTER.
